UNITED STATES PATENT OFFICE.

HORACE LEE FROST, OF ELIZABETHTON, TENNESSEE.

PNEUMATIC PUMP.

1,387,376.

Patented Aug. 9, 1921.

Application filed May 24, 1919. Serial No. 299,399.

To all whom it may concern:

Be it known that I, HORACE L. FROST, a citizen of the United States, residing at Elizabethton, in the county of Carter and 5 State of Tennessee, have invented a new and useful Pneumatic Pump, of which the following is a specification.

This invention has reference to pneumatic pumps, and its object is to provide a pump 10 for water in which the propelling means comprises compressed air.

In accordance with the invention two joined tanks or cylinders are provided and mounted to rock upon a suitable axis, the 15 rocking being caused by the alternate buoyancy of the tanks in the water, in which the tanks are immersed, due to compressed air forcing the water out of one tank while water is permitted to flow into the other tank. 20 The invention includes a valve structure operated by the rocking of the tanks and directing the compressed air in proper order into the tanks, whereby the action of the pump may be continuous or intermittent in 25 accordance with the demand, and such action is entirely automatic.

The invention will be best understood from a consideration of the following detailed description taken in connection with 30 the accompanying drawings forming part of this specification, with the understanding, however, that the invention is not confined to any strict conformity with the showing of the drawings, but may be changed and 35 modified so long as such changes and modifications mark no material departure from the salient features of the invention as expressed in the appended claims.

In the drawings:

40 Fig. 1 is a vertical section through the pump about midway of its width.

Fig. 2 is a section of the pump on the line 2—2 of Fig. 1, but showing the air valve in elevation.

45 Fig. 3 is a plan view of the pump showing the air intake and water outlet pipes in cross section.

Fig. 4 is a longitudinal section through the air valve with some parts in elevation 50 and the valve in one operative position.

Fig. 5 is a view similar to Fig. 4 but showing the air valve in another operative position.

55 Figs. 6 and 7 are sections through a controlling valve forming part of the air valve,

showing different operative positions of said controlling valve.

Referring to the drawings, there is shown a base 1 on opposite sides of which are erected columns 2, 3 respectively, these columns being formed of pipe since the column 2 is used for conducting air under pressure and the column 3 is used for conducting water delivered by the pump, and, for convenience of construction, the columns may 60 be wholly formed of pipe with T-couplings 4, 5 at suitable points. The couplings 5 are joined by pipe sections or long nipples 6, which latter are joined at their meeting ends by flanged couplings 7 clamping an interposed diaphragm 8. The flanged couplings 7 are held together by bolts 9, or otherwise, with the diaphragm 8 tightly secured between them so that the upper ends of the 65 columns 2 and 3 are rigidly united and 70 spaced but have no communication by way of the pipe sections 6.

The T-couplings 4 are located close to but at a suitable distance above the base 1, and extending from the couplings 4 toward each other are pipes 10, 11 respectively, these pipes having exteriorly smooth inner ends 12, 13 respectively. The two pipes 10 and 11 enter aligned chambers 14, 15 at opposite end portions of a casting 16 having diametrically opposite branches 18 entered by nipples 19 which are in communication through a passageway 20 in the casting 16. The outer end of each branch 18 is formed with a radially outstanding flange 21 secured to a 75 boss 22 formed on or fast to the outer wall of a respective tank or cylinder 23, 24, there being two such cylinders at opposite ends of the branches 18 of the casting 16. Each nipple 19 carries a check valve 25 within 80 the respective tanks 23 and 24, the check valves being alike and each provided with a flap 26 closing toward the interior of the cylinder or tank. Each cylinder or tank 23 and 24 has its upper end closed by a head 27 85 and its lower end closed by a head 28, which head 28 has a centrally located passage 29 therethrough surrounded by a ledge 30 and provided with an interior spider 31 carrying a boss 32. There is also provided a 90 plate valve 33 of a size to cover the passage 29 and rest on the ledge 30. The valve 33 is held in place by a stud 34 threaded into the boss 32 and provided with an expanded head 35, whereby the valve may open to a 95 100 105 110

limited extent and will close onto the ledge 30.

The casting 16 constitutes a pivotal support for the cylinders or tanks 23 and 24, and 5 packing glands 36 surround the pipes 10 and 11 to provide fluid tight joints in the pivotal support. Connected to the casting 16 and rising from the chamber 14 is a pipe 37 continued to a greater height than and located 10 between the tanks or cylinders 23 and 24. At the upper end of the pipe 37 is an air valve 38, shown separately in Figs. 4 and 5 with certain details illustrated in Figs. 6 and 7, and reference is had to the named figures 15 for illustration of the air valve structure. Such air valve structure comprises a body member 39 which may be in the form of a cylinder terminating at one end in an outstanding flange 40 to which is applied a head 20 41 closing it and held to the flange by cap screws 42 or in any other suitable manner. The opposite end of the cylinder 39 is provided with a reduced axial extension 43 open at the outer end and the large end of the 25 cylinder where covered by the head 41 is counterbored, for a suitable distance, as shown at 44. Communicating with the counterbore 44 is one end of a pipe 45 connected at the other end to a port 46 leading into 30 the bore of the cylinder 39 adjacent to the reduced extension 43. The pipe 45 includes a valve 47 which may be of any suitable form, but is shown in the drawings as a spigot valve, and this valve is separately 35 shown in Figs. 6 and 7. The valve has a spigot part 48 with a through port or passage 49 and a branch passage 50 communicating with the passage 49 about midway of the length of the latter, the ends of the 40 passages 49 and 50 terminating at the surface of the spigot of the valve. The pipe 45, where interrupted by the valve 47, communicates with the passage 49 through ports 51 on opposite sides of the casing of the valve, 45 and in quadrature with the ports 51 is another port 52 leading through the casing of the valve and opening to the atmosphere, the arrangement being such that in one position of the spigot member 48 the passage 49 constitutes a through passage by way of the 50 valve for the pipe 45, as shown in Figs. 5 and 6, while in another position of the spigot 48, as shown in Figs. 4 and 7, that end of the pipe 45 communicating with the counterbore 44 is open to the atmosphere through 55 the passages 50 and 49 and port 52.

In the reduced end 43 of the air valve there is a passage 53 opening into a groove 54 about the inner face or bore of the extension 43. In the main part of the valve, represented by the cylinder 39, the inner wall thereof is provided with adjacent circumferential grooves 55, 56. The groove 55 opens through a port 57 directly to the atmosphere and the groove 56 is in communica-

cation with a port 58 through the cylinder 39. Connected to the port 53 is a pipe 59 including a flexibly jointed section 60 and at the end remote from the extension 43 opening into the interior of the cylinder or tank 24 through the head 27 thereof. Connected to the port 58 is a pipe 61 similar to the pipe 59 and provided with a flexibly jointed section 62, the pipe 61 communicating with the cylinder or tank 23 through the head 27 thereof.

The spigot 48 of the valve 47 is provided with an operating arm 63 connected by a link 64 with a ring 65 clamped about a respective one of the pipe sections 6, the arrangement being such that the air valve may be rocked to and fro with the pipe 37 and such movement will cause a corresponding rocking of the spigot 48 of the valve 47 to place the two ends of the air valve in communication or connect the larger end of the air valve to the atmosphere.

Within the body portion 39 of the air valve is a sleeve 66 covering the grooves 55 and 56 and there provided with a circular series of perforations 67, 68 respectively, and this sleeve extends from, but does not cover, the port 46 into the counterbore 44 but stops short of the head 41 so that the interior of the sleeve is in communication with the counterbore 44 and consequently with the pipe 45. Within the smaller end 43 of the air valve is another sleeve 69 provided with a circular series of perforations 70 communicating with the groove 54.

Located in and slidable along the sleeve 66 and 69 is a piston composed of piston heads 71, 72 and 73, the latter being located within the sleeve 69 and the heads 71 and 72 being suitably spaced apart and located 105 within the sleeve 66. The several heads are provided with cup leathers or other suitable packing means and are all joined by a rod or stem 74. Between the heads 72 and 73 the 110 slidable valve member has an abutment lug 75 movable to the sleeve 69, thereby limiting the movement of the valve pistons in one direction. The range of movement of the movable member of the air valve made up of the pistons 71, 72 and 73 is such that the 115 piston 72 will override the perforations 68, thereby connecting the ports 57 and 58 or placing the perforations 68 and consequently the port 58 in communication with the exhaust port 57. The range of movement of the piston 73 is such that the port 53 may be placed in communication with the atmosphere through the open end of the extension 43 of the cylinder 39, or the port 53 may be closed by the piston 73 on one side and the 120 abutment lug 75 on the other side.

Let it be assumed that the tanks are in the position shown in Fig. 1 and the main air valve 38 in the position shown in Fig. 5, and let it be further assumed that the 130

cylinder or tank 24 is full of water with the tank 23 about empty and just beginning to fill with water. Under these circumstances the tank 23, which is connected with 5 the air valve by way of the pipe 61, has this pipe open to the atmosphere through the port 58, groove 56, perforations 68, space between the perforations 68 and 67, groove 55, and exhaust port 57, with the atmosphere. As the tanks 23 and 24 are always 10 submerged, water will readily flow into the tank 23, which is assumed to be, at the beginning of this operation, free from water. At the same time main air under pressure 15 is flowing through the tube or pipe 37 into the main air valve and by way of the perforations 70 and passage 54 through the port 53 and pipe 59 into the tank or cylinder 24. This forces water past the valve 20 26 and through the nipple 19 into the passage 20 and thence by way of the pipe 11 into the column 3 to wherever the pump delivers. If the pump is to be in continuous 25 action, as, for instance, operating to fill a reservoir, the flow will continue steadily until the cylinder or tank 24 is emptied. In the meantime, the cylinder 23 is filling. If the demand upon the water supply be intermittent then the discharge of water is 30 intermittent but the tank or cylinder 24 is ultimately emptied although taking a longer time than where the out-flow is continuous. When the buoyancy of the cylinder 24 becomes sufficient to overcome the cylinder 23 35 and parts controlled thereby together with the friction of rocking or sliding parts, the cylinder 23 will drop and the cylinder 24 will be raised. This causes a corresponding bodily movement of the air valve 38 and the 40 change in the position of the spigot 48 of the valve 47 from the position shown in Figs. 5 and 6 to the position shown in Figs. 4 and 7. That face of the piston 71 toward the head 41 is now open to the atmosphere 45 by the change in position of the spigot 48, the said space communicating with the atmosphere through the counterbore 44, pipe 45, passages 50 and 49 to the port 52 which is constantly open to the atmosphere. Now 50 the superior pressure on the piston 72 due to air under pressure over the pressure on the outer face of the piston 71 causes the movement of the air valve toward the head 41, moving the piston 73 in a like direction, the 55 air pressure on the piston 73 being considerably inferior to the pressure on the piston 72 because of the relatively small size of the piston 73 where subjected to the action of the compressed air. The movable structure 60 in the air valve is therefore forced to the position shown in Fig. 4, thereby separating the port 58 from the port 57 because of the interposition of the valve 72. The pipe 45 being now cut off from the main 65 air pipe by the valve spigot of the auxiliary valve 47, the main air pressure is directed through the perforations 68 into the groove 56 and so to and through the port 58, which latter is connected by the pipe 61 to the cylinder 23 and the cylinder 24 is connected 70 by the pipe 59, port 53, groove 54, and perforations 70, with the atmosphere, through the now open end of the extension 43.

Under such position of the parts the cylinder 24 is open to the atmosphere so that 75 water will naturally open the valve 33 and flow into the cylinder with the air in the cylinder readily escaping to the atmosphere, and while this is occurring air under pressure is directed into the cylinder 23 by way of the pipes 2 and 37, perforations 68, groove 56, port 58, and pipe 61. The water in the cylinder 23 is thereby forced from the cylinder through the corresponding valve 26 and nipple 19 into the passage 20 and out 80 through the pipe 11 into the water pipe 3 and so away from the pump. As soon as the cylinder 23 is emptied and the cylinder 24 is sufficiently full of water, the buoyancy 85 of the cylinder 23 will overcome the friction of the parts operated by the cylinders, and the pump returns to the first condition, whereupon the operation, already described is repeated, such operation being slow or rapid in accordance with the outflow of 90 water. Where the demand upon the pump is continuous and full the pump acts with considerable rapidity. Where the demand is small, as, for instance, in households where spigots are opened occasionally, the 95 operation of the pump is correspondingly slow. Nevertheless the operation of the pump is sure and requires no attention whatsoever, being wholly automatic.

What is claimed is:—

1. An automatic pneumatic pump having a compressed air inlet and a water outlet, a rockable pair of cylinders or tanks for submergence in a body of water and having inwardly opening valves for access of water to the tanks, and an air valve rockable with the tanks and arranged for connection with a source of air under pressure, said air valve comprising a differential piston structure and having air connections with the tanks controlled by the piston structure, and an auxiliary valve structure carried by the air valve and responsive to rocking movements of the cylinders and air valve to direct air under pressure to the cylinders in alternation and connect the cylinders in similar manner to the atmosphere.
2. An automatic pneumatic pump comprising a rockable pair of connected tanks or cylinders for receiving and discharging water and designed to be submerged in a body of water, a supporting frame for the tanks including columns constituting air and water pipes, connections between the pipes and the tanks for conducting air to

and water from the tanks by way of the columns and also constituting the pivotal support for the tanks, and an air valve connected to the air side of the pivotal support 5 and participating in the rocking movements of the tanks, said air valve being provided with a reciprocatory piston structure and with air ports and connections to the tanks and the air valve participating in the rocking movements of the tanks for causing the 10 operation of the piston structure by the compressed air.

3. A pneumatic pump comprising a pair of tanks or cylinders with a duct joining 15 them and at the ends entering the tanks and these provided with check valves closing toward the interior of the tanks, oppositely directed air and water ducts carrying the first-named duct and constituting a pivot 20 for the tanks, a pneumatically operated valve structure participating in the rocking movements of the tanks and connected to the air duct and to the respective tanks, and means responsive to the rocking movements of the 25 tanks for controlling the flow of air through the valve structure.

4. A pneumatic pump comprising a pair of tanks or cylinders, with a duct joining them and at the ends provided with check 30 valves opening away from the interiors of the cylinders, said duct being provided with oppositely directed swivel connections, air and water ducts entering and supporting the swivel connections whereby the latter 35 constitute a pivot support for the tanks on which the tanks may rock, a pneumatically operated valve structure connected to the air duct and participating in the rocking movements of the tanks, said structure having air connections to both tanks, and means 40 responsive to the rocking movements of the tanks for controlling the flow of air from the air duct to the tanks in alternation.

5. A pneumatic pump comprising a pair 45 of tanks or cylinders, with a duct joining them and at the end provided with check valves opening away from the interiors of the cylinders, said duct being provided with oppositely directed swivel connections, air 50 and water ducts entering and supporting the swivel connections whereby the latter constitute a pivot support for the tanks on which the tanks may rock, a pneumatically operated valve structure connected to the 55 air duct and participating in the rocking movements of the tanks, said structure having air connections to both tanks, and means responsive to the rocking movements of the tanks for controlling the flow of air from the air duct to the tanks in alternation, said 60 valve structure including means whereby air directed to the tanks may be exhausted therefrom to permit the filling of the tanks with water.

6. In a pneumatic pump having rockably

mounted tanks, and a valve structure comprising a cylinder with a bore smaller at one end than at the other, a piston within the cylinder having longitudinally spaced heads at one end to fit the larger bore, and a single head at the other end to fit the smaller bore, the cylinder having longitudinally disposed ports in position to be overridden by certain of the heads, and a valved by-pass between the end portions of the 70 larger part of the cylinder with means for controlling the valve in the by-pass by rocking movements of the tanks.

7. In a pneumatic pump having rockably mounted tanks, and a valve structure participating in the rocking movements of the tanks and comprising a cylinder with a bore smaller at one end than at the other, a reciprocable piston in the cylinder with longitudinally spaced heads to fit the larger bore 85 and a single head to fit the smaller bore, said cylinder having longitudinally spaced ports in position to be overridden by certain of the heads, and a by-pass between the end portions of the larger part of the valve cylinder 90 and controlled by the rocking movements of the tanks and valve structure.

8. A pneumatic pump comprising rockable tanks joined for alternate filling and discharge and adapted to be submerged in 95 a body of water, and a valve structure carried by the tanks and participating in the rocking movements thereof, said valve structure comprising a cylinder with a bore larger at one end than at the other, a piston 100 reciprocable in the bore and having at one end longitudinally spaced heads to fit the larger part of the bore and a single head at the other end to fit the smaller part of the bore, said cylinder having longitudinally 105 disposed ports in position to be overridden by certain of the heads, with certain of the ports opening to the atmosphere and others of the ports connected to the respective tanks, and means controlled by the rocking 110 movements of the tanks and valve cylinder to divert air under pressure in alternation to the cylinders and to similarly exhaust air from the cylinders.

9. A pneumatic pump comprising a rockable pair of joined tanks adapted to be submerged in water, and a valve structure carried by the tanks and participating in the rocking movements, said valve structure comprising a cylinder having a bore smaller 115 at one end than at the other, the cylinder also having intermediately located compressed air and exhaust ports in the larger part of the cylinder, a valved by-pass between the ends of the larger part of the 120 cylinder, compressed air and exhaust ports in the smaller end of the cylinder, and a piston structure in the cylinder with spaced heads and movable to override certain of 125 the ports.

10. A pneumatic pump comprising a rockable pair of joined tanks, a support carrying the tanks and in which it is rockable, said support including an inlet duct for compressed air and an outlet duct for water, and a valve structure interposed between the compressed air ducts and the tanks, said valve structure comprising a cylinder with a bore of different sizes at opposite ends, a 10 reciprocable piston within the cylinder having heads of different sizes corresponding to the different bores of the cylinder, spaced air and exhaust ports in the cylinder with

the air ports connected to respective tanks, and a by-pass between opposite ends of the 15 larger part of the cylinder and provided with a valve responsive to rocking movements of the tanks and valve structure, whereby the rocking of the tanks causes the alternate feeding of compressed air to the 20 tanks and the escape of used air therefrom.

In testimony that I claim the foregoing as my own I have hereto affixed my signature.

HORACE LEE FROST.
